Patented Dec. 17, 1974

233,933

DISPENSING CONTAINER FOR DEODORANTS OR THE LIKE

David Mahler, 9023 Hopen Place,
Los Angeles, Calif. 90069

Filed June 5, 1972, Ser. No. 260,046

Term of patent 14 years

U.S. Cl. D23—150 Int. Cl. D23—04

FIG. 1.

FIG. 3.

FIG. 2.

FIG. 4.

FIG. 1 is a top plan view of a dispensing container for deodorants or the like showing my new design;

FIG. 2 is an elevational view;

FIG. 3 is a bottom plan view; and

FIG. 4 is a fragmentary view thereof, partially in section, taken on the line 4—4 of FIG. 2.

I claim:

The ornamental design for a dispersing container for deodorants or the like, substantially as shown.
